US0D1021350S

(12) United States Design Patent (10) Patent No.: US D1,021,350 S
(45) Date of Patent: * Apr. 9, 2024

(54) SHOE

(71) Applicant: Converse Inc., Boston, MA (US)

(72) Inventor: Alyssa Makere, Boston, MA (US)

(73) Assignee: Converse Inc., Boston, MA (US)

() Term: 15 Years

(21) Appl. No.: 29/897,589

(22) Filed: Jul. 17, 2023

(51) LOC (14) Cl. 02-04

(52) U.S. Cl.

USPC D2/969; D2/916

(58) Field of Classification Search

USPC D2/896-900, 902-904, 906-908,

CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is an opposite side rear perspective view thereof;

FIG. 5 is an opposite side view thereof; and,

FIG. 6 is an opposite side front perspective view thereof. The broken lines depicting the strap ends, the two strap eyelets, and the remainder of the shoe form no part of the claimed design.

1 Claim, 6 Drawing Sheets
